UNITED STATES PATENT OFFICE.

HOMER C. CHALK, OF SAN ANTONIO, TEXAS.

ATTACHMENT FOR PRESSES.

Application filed October 28, 1921. Serial No. 511,043.

To all whom it may concern:

Be it known that I, HOMER C. CHALK, a citizen of the United States, residing at San Antonio, in the county of Bexar and 5 State of Texas, have invented new and useful Improvements in Attachments for Presses, of which the following is a specification.

My present invention has reference to a 10 hay press attachment, and is designed to facilitate the wiring of the hay compressed in such presses.

An object is to produce an attachment of this character which can be applied to any 15 ordinary construction of hay baling presses, and wherein the wires will be positively fed so that the bale can be wired by a single operator.

A further object is to produce a wiring 20 attachment for hay presses which shall be of a comparatively simple construction, cheap to manufacture and market, readily arranged upon the press and which will be positive and accurate in operation.

25 The foregoing, and other objects which will appear as the nature of the invention is better understood, may be accomplished by a construction, combination and operative association of parts, such as is disclosed 30 by the drawings which accompany and which form part of this specification.

In the drawings:—

Figure 1 is a perspective view of a portion 35 of a press having the improvement applied thereto.

Figure 2 is a similar view upon a greatly enlarged scale and showing the arrangement of parts when the division blocks have been moved into the baling chamber.

40 Figure 3 is a horizontal sectional view taken directly above the upper telescopic tubes, as disclosed in Figure 2.

Figure 4 is a fragmentary sectional view 45 illustrating the manner in which the spring influenced pin is held in its pocket when a division block is in the press before the removal thereof into the baling chamber.

Figure 5 is a fragmentary transverse sectional view on the line 5—5 of Figure 2.

50 Figure 6 is a sectional view on the line 6—6 of Figure 3.

Figure 7 is a detail view of one of the guides.

55 Figure 8 is a detail sectional view through one of the division blocks.

Referring now to the drawings in detail,

a baling press of the ordinary construction is indicated by the numeral 1, 2 indicating the feeding chamber, and 3 the baling chamber thereof. The baling chamber, has its 60 upper and lower boards, at its outer end compressed by the usual spring influenced means which is broadly indicated by the numeral 4, whereby the outer division block will be retarded in its travel through the 65 said baling chamber.

The division blocks between which the bale is compressed are indicated by the numeral 5 respectively. As is well known, one 70 of the division blocks 5 is retained in the baling chamber when the other division blocks are in the press. Both boards 5, in the present instance, have their opposite faces, adjacent their top and bottom edges provided with oppositely arranged transverse 75 grooves 6, and in each of these grooves there is a wire guide 7. Each guide is constructed of metal to include a flat base which is screwed or otherwise secured in the inner wall of the grooves 6, from the base there 80 being extended arched sides 8 that terminate a slight distance away from each other, providing the guides with a central wire opening therethrough. With this construction it is not possible that the grooves be 85 filled by obstructing material, as is common with the ordinary arrangement of such grooves and also with this construction the material cannot interfere with the wire.

Each division block 5, between the oppositely arranged wire guides has one of its edges provided with a pocket 9 and within this pocket there is pivoted, as at 10 the inner arm of an angle member 11. For the purpose of this description, the outer arm of 95 the member 11 will be referred to as the finger thereof, the said finger being provided with a ball head 12, and the member 11 being influenced by a spring 13 to project the finger and the ball head through the 100 pocket 9. The angle member 11 is swung upon its pivot 10 when the same is received in the baling press, but when the division block is moved to bring the same into the baling chamber, the spring will influence the 105 member 11 to project its finger 10 through the open sides of the said baling chamber.

In addition to the division block construction, my improvement contemplates the employment of means for guiding the wire 110 from one side of the press around the bale, the said means including a frame 14 which is

provided with U-shaped ends the upper and lower parallel elements of the frame being disposed over the respective upper and lower boards of the baling chamber 3, the upper members or arms having threaded openings that receive therethrough binding screws 15 that contact with the upper board of the baling chamber. The parallel or angle arms of the members 14 are connected by longitudinal strips 16 respectively, and the outer or vertical portions of the members 14 are provided with elongated slots 17. Through these slots 17 pass bolts 18 that are secured on the outer portions of substantially U-shaped members 19. The arms 20 of the U-shaped members 19 are arranged parallel with the arms of the U-shaped members 14, and the bolts 18 are engaged by nuts 21, whereby the auxiliary frame, whose ends are provided by the U-shaped members 19 may be adjusted vertically on the main frame. The arms 20 of the auxiliary frame have arranged thereon plates 22 respectively. These plates are pivoted, as at 23 to the arms 20 of the outer U-shaped member 19, the arms 20 of the inner U-shaped member being bent upon themselves to provide overlying lips or flanges 24 that receive therein the opposite ends of the plates 22.

Each of the plates 22 has its outer edge formed with an upturned flange 25, and each of the said flanges is provided with an inwardly directed curved end 26.

Secured centrally on each of the plates 22 is a tubular split sleeve 26'. Each sleeve has secured on its outer face a hook 28. The sleeves 26' provides guides for telescopic tubular members 29 and 30 respectively. Each of these members has its inner face provided with a slot 31 and 32 respectively which are in registering alignment and also in alignment with the slot provided by the split sleeves 26. The ends of the tubes 29 and 30 are rounded upon themselves and are normally retained in contacting engagement with the rounded ends 26 of the flanges 25 on the plates 22. The rounded end of the tube 29 is indicated by the numeral 33, and that of the tube 30 by the numeral 34. The end 33 is of a diameter equalling that of the tube 29, but the end 34 of the tube 30 is gradually reduced so that the said end is of a substantially spout formation.

Between the hooks 28 and the rounded ends 33 of the tubes 29 there are secured helical springs 35 and between the ends of the tubes 30 and the flanges 24 of the members 20 of the inner U-shaped member 19 there are similar springs 36.

On the rounded ends 33 and 34 of the respective tubes 29 and 30 there are secured what I will term guide members for the fingers 11 of the division blocks. The guide members are each constructed of two spring

plates having their outer ends straight, as at 37 and from thence rounded inwardly, as at 38, terminating in straight extensions 39, which are flared away from each other. The spring plates are connected by the arms 70 of a substantially U-shaped spring member 40, and it is preferably to the upper face of these members that the rounded ends 33 and 34 of the tubes 29 and 30 are secured.

The inner straight and oppositely flared portions 39 are in a position to receive the finger 11 of the inner division block, when the latter has been forced with the outer division block into the baling chamber. A further movement of this division block 80 will permit of the ball head 12 on the fingers thereof riding between the spring plates of the guides, and passing over the inwardly inclined portion 38 will draw the rounded end 34 of the tube 30 toward the division block 5, bringing the mouth of the said ends 34 opposite the transverse grooves 7 in the said board and the slotted portions of the tubes in alignment with the slotted or centrally divided portion of the wire guide 8. A further movement of the division block through the baling chamber will cause the tube 30 to be telescoped in the tube 29. In the meantime, a similar action has taken place between the finger 11 and the guide on the curved ends 33 of the tubes 29, drawing the said ends inwardly toward the outer division block 5 and bringing the mouths of the said tube 29 into registering alignment with the grooves in the outer board. This permits the operator, who stands upon the opposite side of the machine, to pass wires through the wire guides in the outer division block causing said wires to be directed through the telescoped tubes, forcing the end of the wire through the spout-like end 34 of the tube 30, through the wire guides on the inner division block 5, thus permitting the bale to be tied by a single operator. On the outer member of the main frame there are shoes 41 that are in the path of contact with the spring influenced pivoted fingers 11 and engaging said fingers will again force the same against the tension of their springs into their pockets 9. The division block, which I have referred to as the inner division block will be in the position shown in Figure 1 of the drawings, when the division block which I have referred to as the outer division block has been moved through the baling chamber and the bale removed from the said chamber.

With my improvement, it will be noted that the wire will be positively guided in an easy, expeditious and thoroughly accurate manner, and that only one hand is required in directing the wire around the bale. Also with my improvement the liability of clogging of parts is entirely pre-

vented. When the finger has passed through the guides of the inner division block, the springs 35 and 36 will permit of the telescopic tubes 29 and 30 moving 5 outward from each other and return the said tubes to their initial position whereby the curved ends thereof will be in contacting engagement with the curved ends 26 of the flange 25, and it is thought from the foregoing description, when taken in connection with the drawings that the construction, operation and advantages of the improvement will be apparent to those skilled in the art to which such inventions 10 relate. It is also thought necessary to state that the showing and description have reference to a satisfactory embodiment of the invention as it now appears to me and that I am entitled to make all such changes 15 therefrom as fall within the scope of what is claimed.

Having described the invention, I claim:—

1. A baling press having grooved wire receiving division blocks movable between the feeding and baling chamber thereof, and the last mentioned chamber having open sides and having means for halting the movement of the outer division block, when the inner division block is moved toward 25 the outer division block for producing a bale between the division blocks, of slotted telescopic tubes supported at one side of the baling chamber and having curved ends directed toward said chamber, spring means between the tubes for sustaining the same in expanded position, means carried by the division blocks for engaging the tubes to telescope the same during the movement of the division blocks and for 30 drawing the curved ends of the tubes into alignment with the wire receiving slots of the said division blocks when the division blocks are in bale pressing position, whereby to permit of wire being inserted through 35 the grooves of one of the division blocks to cause the same to pass through the tubes and to be directed through the slots of the second division block to permit of the ends of the wire being twisted together, and said means, 40 in a further movement of the division blocks, releasing the tubes and permitting the springs to return the same to initial position. 45
2. A baling press having grooved wire receiving division blocks movable between the feeding and baling chamber thereof, and the last mentioned chamber having open sides and having means for halting the movement of the outer division block, when 50 the inner board is moved toward the outer division block for producing a bale between the division blocks, of a frame removably secured to one side of the baling chamber, slotted telescopic tubes supported on the 55 frame and having curved ends directed to- ward the baling chamber, spring means holding the tubes in one position, means on the division blocks for engaging the tubes to telescope the latter during the movement of the division blocks through the baling 70 chamber and to draw the curved ends of the said tubes toward the division blocks to bring the same in alignment with the wire grooves in the division blocks whereby wires may be passed through the grooves 75 in one of the division blocks, through the tubes and through the grooves in the other division block around the bale compressed between the division blocks and at the ends of the wire twisted together, and said means 80 designed to release the tubes on a further movement of the division blocks to permit of the springs returning the tubes to initial position. 85
3. A baling press having grooved wire receiving division blocks movable between the feeding and baling chamber thereof, and the last mentioned chamber having open sides and having means for halting the movement of the outer division block, when the inner 90 division block is moved toward the outer board for producing a bale between the division blocks, of a frame removably supported at one side of the baling chamber, a second vertically adjustable frame supported 95 on the first mentioned frame, slotted telescopic tubes supported on the last mentioned frame, said tubes having curved ends directed toward the baling chamber, spring means holding the tubes in 100 suspended position, means carried by the division blocks susceptible to outward movement when the division blocks have been moved into the baling chamber and designed to engage with the tubes to collapse the same 105 during the pressing operation of a bale between the division blocks and to further draw the curved ends of the tubes into alignment with the wire grooves in the division blocks, whereby to permit wires being 110 inserted through the grooves of one of the division blocks, the telescoped tubes and the wire grooves in the other division blocks to allow said wires to be arranged around the bale and to have its ends twisted together, 115 and said means, upon a further movement of the division blocks releasing the said tubes and permitting the springs thereof returning the same to initial position. 120
4. A baling press having grooved wire receiving division blocks movable between the feeding and baling chamber thereof, and the last mentioned chamber having open sides and having means for halting the movement of the outer division block, when 125 the inner division block is moved toward the outer division block for producing a bale between the division blocks, of a detachable frame secured to one side of the baling chamber, a second vertically adjustable 130

- frame on the first mentioned frame, horizontally disposed plates on the last mentioned frame having flanges provided with inwardly curved ends, a slotted sleeve secured centrally on each of the plates, slotted telescopic tubes guided through the sleeves having curved ends normally in contacting engagement with the curved ends of the flanges, spring means holding the tubes in such position, spring influenced means on the division blocks designed, when the latter are moved from the press into the baling chamber thereof to move outward from the division blocks and to engage with the tubes to telescope the same in the longitudinal movement of the division blocks and to bring the curved ends of the said tubes in alignment with the wire receiving grooves in the division blocks, whereby wires may be inserted through the grooves of one of the division blocks, directed through the tubes into and through the wire grooves of the second division block and around the bale compressed between the division blocks and to permit of the twisting together of the ends of the wires, and said means upon a further movement of the division blocks designed to release the tubes to permit of the tubes influencing the latter to initial position.
5. A baling press having grooved wire receiving division blocks movable between the feeding and baling chamber thereof, and the last mentioned chamber having open sides and having means for halting the movement of the outer division block, when the inner division block is moved toward the outer division block for producing a bale between the division blocks, of vertically adjustable telescopically associated slotted tubes supported at one side of the baling chamber and having inwardly curved ends, and the curved end of one of each of the tubes being reduced, spring means holding the tubes expanded, offset spring guides secured to the curved ends of the tubes, normally housed spring influenced means carried by the division blocks designed to be brought to outer position when the division blocks have passed into the baling chamber and further designed to engage the guides to telescope the tubes during the compression of a bale between the division blocks and to bring the curved ends of the tubes into register with the wire grooves in the division blocks when the baling operation is completed, whereby baling wires may be passed through the grooves in one of the division blocks, directed through the telescoped tubes into and through the wire grooves of the second division block around the bale and to permit of the tying of the ends of the wire, the strand of the wire received through the tubes designed to be passed through the slots therein in the tying operation of the wire, and said tube influencing means designed to ride off of the guides when the division blocks are further moved to permit of the outward movement of the telescopic tubes and the return of the latter to initial position.
6. A baling press having grooved wire receiving division blocks movable between the feeding and baling chamber thereof, and the last mentioned chamber having open sides and having means for halting the movement of the outer division block, when the inner division block is moved toward the outer division block for producing a bale between the division blocks, of slotted telescopic tubes having curved ends supported at one side of the baling chamber, spring means holding the tubes in extended position, and said tubes having curved ends directed toward the baling chamber, angularly arranged guides on the curved ends of the tubes, each guide comprising a pair of spaced plates flared away from each other at one end to provide a passage therebetween, and spring means holding the opposite ends of the plates against each other, said division blocks having spring influenced fingers provided with ball ends pocketed in the edges thereof and housed in said pockets when the division blocks are in the press and designed to move out of said pockets when the division blocks are in the baling chamber, and said fingers, when in their last mentioned position, designed to be received between the guides to exert a pressure thereagainst to collapse the tubes and draw the curved ends thereof toward and in alignment with the wire grooves of the division blocks when a bale has been compressed between the division blocks, and whereby wires may be passed through the wire grooves in the outer division block and directed through the telescoped tubes to and through the wire grooves in the second division block to permit the wires being arranged around the bale and the ends thereof twisted together, and said fingers upon a further movement of the division blocks and bale traveling off of the guides to permit the tubes being returned to initial projected position, and means upon the outer end of the baling chamber for rehousing the fingers of the division blocks.
7. A baling press having grooved wire receiving blocks movable between the feeding and baling chamber thereof, and the last mentioned chamber having open sides and having means for halting the movement of the outer division block, when the inner division block is moved toward the outer division block for producing a bale between the division blocks, the grooves of the said division blocks having metallic guides therein, comprising plates having their sides rounded toward each other and terminating

away from each other to provide a slot between the said curved portions, telescopically associated slotted tubes supported at one side of the baling chamber and having 5 curved ends directed toward the baling chamber, spring means holding the tubes in extended position with respect to each other, means on the division blocks for engaging the tubes, when the division 10 blocks are moved into the baling chamber, to telescope the tubes and to draw the curved ends thereof toward the division blocks and bring the same in alignment with the wire guides in the grooves of the division 15 blocks when the division blocks have com-
pressed a bale therebetween, whereby wires may be directed through the guide in the outer division block, passed through the telescoped tubes and directed therefrom through the wire guides in the inner division block 20 and tied around the bale, said wires passing through the slots of the guides and the slots in the tubes when in tied condition, and said means designed to release the tubes, when the division blocks are further moved in the 25 baling chamber to permit of the said tubes being returned to normal expanded position.

In testimony whereof I affix my signature.

HOMER C. CHALK.
